UNITED STATES PATENT OFFICE.

JAMES T. ANDREW, OF MONTGOMERY, ALABAMA.

RAILWAY SAFETY APPLIANCE.

986,261.

Specification of Letters Patent. Patented Mar. 7, 1911.

Application filed November 18, 1910. Serial No. 593,095.

To all whom it may concern:

Be it known that I, JAMES T. ANDREW, a citizen of the United States, residing at Montgomery, in the county of Montgomery and State of Alabama, have invented certain new and useful Improvements in Railway Safety Appliances; and I do hereby declare the following to be a full, clear, and exact description of the invention, such as will enable others skilled in the art to which it appertains to make and use the same.

This invention relates to railway safety appliances, and has for its object to improve the invention disclosed in my prior Patent 15 941,222, issued November 23, 1909.

To this end, the invention consists in the novel details of construction and combinations of parts more fully hereinafter disclosed and particularly pointed out in the 20 claims.

Referring to the accompanying drawings forming a part of this specification, in which like numerals refer to like parts in all the views:—Figure 1 is a longitudinal sectional view of the truck of a locomotive, with my 25 improvements attached thereto; Fig. 2 is a sectional detail view of certain of the portions shown in Fig. 1; and Fig. 3 is an elevational view of a hanger for the safety rollers detached from the truck.

1 indicates the track, 2 the wheels of a locomotive, 3 the axles and 4 one of the side bars of the truck. On the axles 3 I provide inside of the wheels 2 at each end hangers 5, preferably of the general shape shown in 30 Fig. 3. These hangers are provided with orifices 6 through which pass the axles 7 of the safety rollers 8, which are located slightly above track 1, as shown. Extending from end to end of the truck underneath the axles 3, is a continuous beam 10, which is provided with U-shaped supporting brackets 11, passing down underneath and around the axle 7. The hangers 5 are provided with cut-away places 12 to accommodate the brasses 13 and with cut-away places 14 to accommodate the lubricating portion of the journal box. Passing underneath the journal boxes are plates 16, fitting in slots 17 in the hangers, and which are secured in place by the bolts 18, as shown. Upon taking out the bolts 18 and removing the plates 16, the hangers 5 can be readily removed from the axles 3.

55 Connecting the hangers 5 is a bar 21, which steadies and braces the same, and re-

sists any twisting or distorting strains. Between the axles 7 and the beam 10 are a number of pressure blocks 22, which when the engine is derailed, and the strain is 60 brought upon the rollers 8, serve to transmit the strain from the axles 7 to the beam 10, which in turn transmits said strain to the main axles 3 of the truck, as will be readily understood. In the same way this strain is 65 transmitted through the plates 16 and box 40 to the axles 3, as will be clear from Fig. 1.

The extreme forward and rear safety rollers 25 are provided with a conical bore 26, as illustrated in Fig. 2, and also with a 70 circumferential groove 27, in which fits a segment of a ring 28, Fig. 1, attached to the spring-pressed-rod 29, controlling the air valve 30, and connected by the pipe 31 to the air-brake system.

75 The operation of my invention is as follows:—As clearly disclosed in my former patent above, when the engine leaves the track, the safety rollers 25 on one side of the truck receive the weight of the engine and 80 truck on one rail, while wheels such as 35 on the other side of the engine receive the weight of said engine and truck on the other rail. In the present invention, however, when the forward or rear rollers 25 come in 85 contact with the rail, the said rollers will be lifted, owing to their conical bore, and will thereupon raise the spring-pressed rod 29, to operate the air valve 30, and to automatically apply the brakes to the train. In all 90 cases the weight which comes upon the safety rollers 8 and 25 is transmitted through the axles 7 to the longitudinal beam 10, which in turn transmit the strain to the main axles 3 of the truck. A portion 95 of this strain is also transmitted through the plates 16 and box 40 to the main axles 3, as above indicated.

It is obvious that those skilled in the art may vary the details of construction and the 100 arrangement of parts without departing from the spirit of my invention, and, therefore, I do not wish to be limited to such features as disclosed, except as may be required by the claims.

105 The brake applying mechanism of this case is not claimed herein, but is made the subject of my divisional application #600,622, filed Jan. 3, 1911.

What I claim is:—

110 1. In a railway safety appliance the combination of a truck provided with main

axles; a longitudinal beam extending under said axles; a plurality of safety axles under said beam; and connections through which strains may be transmitted from said safety axles to said beam and from said beam to said main axles, substantially as described.

5. In a railway safety appliance the combination of a truck provided with main axles; a longitudinal beam extending under 10 said axles; a plurality of safety axles under said beam; hangers supported from said main axles through which said safety axles pass; safety rollers on said safety axles; and connections through which strains may 15 be transmitted from said safety axles to said beam and from said beam to said main axles, substantially as described.

3. In a railway safety appliance the combination of a truck provided with main 20 axles; hangers provided with recesses to accommodate portions of the journal boxes on said axles; safety axles supported from said hangers; and a longitudinal beam crossing said safety axles, substantially as described.

25. 4. In a railway safety appliance the combination of a truck provided with main axles; hangers provided with recesses to accommodate portions of the journal boxes on said axles; connections between each pair of

hangers; safety axles supported from said 30 hangers; a longitudinal beam connected to said safety axles; and connections between said beam and safety axles adapted to transmit strains from the latter to the former, substantially as described.

35. 5. In a railway safety appliance the combination of a truck provided with main axles; hangers provided with recesses to accommodate portions of the journal boxes on 40 said axles; connections between said hangers; safety axles supported from said hangers; a longitudinal beam joining said safety axles, adapted to contact with said main axles; connections between said safety axles and said beam adapted to transmit strains to and through said beam to said main axles; and connections between the lower portion of said hangers and said 45 main axles adapted to transmit strains from said safety axles to said main axles, substantially as described.

50. In testimony whereof, I affix my signature, in presence of two witnesses.

JAMES T. ANDREW.
